Patented Aug. 17, 1926.

UNITED STATES PATENT OFFICE.

FLOYD K. THAYER, OF CHICAGO, ILLINOIS, ASSIGNOR TO ABBOTT LABORATORIES,
OF CHICAGO, ILLINOIS, A CORPORATION OF ILLINOIS.

ANTISEPTIC ANÆSTHETIC MEDICAMENT.

No Drawing.

Application filed February 27, 1924. Serial No. 695,574.

My invention relates to the use of picrates of local anæsthetics for the treatment of burns and other painful, denuded skin lesions.

In the treatment of burns and painful, denuded skin lesions, the following precautions are necessary, if the patient is to be relieved of suffering and rapid healing promoted:

10 1. The pain and the shock must be relieved.

2. Measures must be taken to prevent infection, such as the application of antiseptic dressings or the use of antiseptic washes.

15 3. The substances used to obtain the above results must not be so strong nor so corrosive in their action as to prevent rapid healing.

Of the chemical compounds which have 20 been used heretofore for the treatment of burns and painful, denuded skin lesions, none has had the properties necessary to fulfill all of the above conditions to a satisfactory degree. Ichthyol and its salts, zinc 25 oxide, aluminium compounds and lime, fulfill the second condition (antisepsis), but lend little or nothing in the way of analgesic properties. Phenol, resorcinol and picric acid also act as antiseptics, but in the dilu-

tions used have only the very faintest pain 30 relieving properties; whereas were the concentrations of these compounds to be increased to a point where analgesia would be noticed, such corrosive action would take 35 place upon the broken epidermis that not only would healing be greatly retarded, but sloughing of the tissue might be expected.

The ointments, salves, and unguents which 40 have been used heretofore for the treatment of burns and painful denuded skin lesions, are, for the most part, made up of a mixture of two or more of the chemical compounds mentioned in the preceding paragraph incorporated in an oily base. Here 45 are usually found the necessary ingredients for antisepsis, but whatever pain relieving properties that are to be found are, in the main, due to the oily nature of the carrier. It is well known that oily or 50 greasy materials lend somewhat to the relief of the sting of burns.

In contradistinction to the already mentioned chemical compounds and ointments, unguents, salves, etc., picric acid salts of 55 local anæsthetics, as employed by me, do ful-

fill the above enumerated conditions. Furthermore, the analgesic action of my preparations—picric acid salts of local anæsthetics, incorporated in oily bases—does not depend alone upon the oily nature of the 60 carrier, but utilizes this soothing property only as an adjunct to the definite anæsthesia which is produced by the action of a salt of a local anæsthetic; and I wish to point out still further that the picric acid is not free 65 picric acid but it is combined chemically with the local anaesthetic, bringing about antiseptic and germicidal action, which keeps the burn and denuded skin lesions free from 70 infection.

General method of synthesizing picric acid salts of local anæsthetics.

One mol. of picric acid and three mols. 75 of the local anæsthetic are reacted in a suitable solvent, such as water, alcohol or benzol. The picric acid salt of the local anæsthetic precipitates as a more or less insoluble salt. It is then filtered, washed and dried. That 80 this product is a chemical compound and not a mixture, can readily be shown by both chemical and pharmacological tests.

Specific compounds.

1. The picric acid salt of n-butyl-p-aminobenzoate, which is a yellow solid melting at 109°–110° C.

2. The picric acid salt of ethyl-p-aminobenzoate, which is a yellow solid melting at 120°–121° C.

3. The picric acid salt of methyl-m-aminop-hydroxy-benzoic acid, which is a yellow solid melting at 221°–222° C. (with decomp.).

4. Procaine Picrate. This is the picric 95 acid salt of diethylamino-ethyl-p-aminobenzoate, and is a yellow solid, melting at 133°–134° C.

5. The picric acid salt of di-n-butyl-amino-propyl-p-aminobenzoate, which is a 100 yellow solid, melting at 85°–88° C.

All of the above compounds are prepared by the general method above described.

In applying my invention, I prefer to incorporate a small percentage of the picrate 105 salt in an oily base. For example: A base is prepared which consists of two parts white wax, two parts paraffin, nine parts mineral oil, three parts water, and one-twelfth part borax; to this base there is 110

added 1% by weight of the picric acid salt of n-butyl-p-aminobenzoate, which has previously been intimately mixed with a small quantity of the above mentioned base; 5 thorough mixing produces a homogeneous ointment having a yellow color.

The scope of the invention is to be determined by reference to the appended claims, said claims to be construed as broadly 10 as possible consistent with the state of the art.

I claim as my invention:

1. As a new article of manufacture, a picrate of an aromatic acid ester, having an 15 amino group in the aromatic nucleus.

2. As a new antiseptic compound having pronounced anæsthetic properties, a picrate of an aminobenzoic acid ester.

3. As a new article of manufacture, a 20 picrate of n-butyl-p-aminobenzoate.

4. As a new article of manufacture, the compound

which is a yellow crystalline solid melting at $109^{\circ}\text{--}110^{\circ}$ C., and having both antiseptic and anæsthetic properties.

FLOYD K. THAYER.
